United States Patent Office

Des. 227,080

Patented June 5, 1973

227,080

RAZOR CASE

Norman D. Poisson, Andover, Mass., assignor to The
Gillette Company, Boston, Mass.

Filed July 19, 1971, Ser. No. 164,184

Term of patent 14 years

Int. Cl. D9—03

U.S. Cl. D9—186

Fig. 1

Fig. 2

Fig. 3

Fig. 4Fig. 5Fig. 6Fig. 7

FIG. 1 is a perspective view of a razor case with the top open showing my new design;

FIG. 2 is a perspective view thereof with the top closed;

FIG. 3 is a plan view thereof;

FIG. 4 is a front elevational view thereof;

FIG. 5 is a rear elevational view thereof;

FIG. 6 is an elevational view of the left end of the case as viewed in FIG. 4; and

FIG. 7 is an elevational view of the right end of the case as viewed in FIG. 4.

I claim:

The ornamental design for a razor case, as shown.
